INVENTOR

By his Attorneys *Henry D. Cushman,*
Baldwin Hopkins & Dayton.

UNITED STATES PATENT OFFICE.

HENRY D. CUSHMAN, OF THREE RIVERS, MICHIGAN.

INHALER.

SPECIFICATION forming part of Letters Patent No. 351,744, dated November 2, 1886.

Application filed June 19, 1886. Serial No. 205,636. (No model.)

To all whom it may concern:

Be it known that I, HENRY D. CUSHMAN, of Three Rivers, in the county of St. Joseph and State of Michigan, have invented an Improved Open Stopper for Inhalers, &c., of which the following is a full description, reference being had to the accompanying drawings.

The object of my invention is to provide an open or perforated stopper for inhalers, smelling-bottles, and other uses, which is adapted to be self-supporting—that is, to hold itself in position within a hollow tube, vessel, or cylindrical body, and that can also, if desired, be used in connection with any ordinary stopper—of cork, for example—as well as alone.

In the drawings, Figure 1 is a longitudinal sectional view of an inhaler with my stopper applied. Fig. 2 is a view of a perforated blank 20 for forming such a stopper as shown in Fig. 1. Fig. 3 is a perforated scalloped blank for forming such a stopper as shown in Fig. 4. Fig. 5 is a perforated stopper with a cork in it.

A indicates a perforated blank of metal; or 25 it might be of some peculiar paper, vulcanized fiber, or other substance having the proper quality for the use contemplated. This blank can be stamped or punched out of a thin plate—of metal, for example—either slitted or 30 scalloped around its margin, as illustrated in Figs. 2 and 3. Then the blank can be formed in suitable dies into cup shape, as is well understood by metal-workers, as shown in Figs. 1 and 4. It will be better to bend the scalloped radial projections of the blank a little, 35 as illustrated.

When the cup-shaped perforated stopper is formed, its margin is notched or slitted, and is

of greater diameter than its bottom part, so that as it is forced into a tube of proper size 40 it will bear outward against the walls of the tube and hold itself in place. It would be easy to change its form to rectangular, hexagonal, octagonal, &c., without departing from the substance of my invention.

The entire stopper may be perforated with numerous holes, or only one hole may be made through it; the number is immaterial. It can be used alone, or an open or closed stopper can be used with it to extend within it, as illustrated, B in Fig. 5 being such a stopper.

I am aware that an open or perforated cup-shaped metal-plate stopper is not broadly new, and I do not claim it; but my improved open stopper, made from a single piece of thin metal 55 in cup shape, with its rim notched or slotted, is new, and has marked practical advantages, in that it can be easily inserted in varying-sized tubes, when it will hold itself in place, and may be adjusted or removed conveniently 60 at will.

Having described my invention, what I claim, and desire to secure by Letters Patent of the United States, is—

As a new article of manufacture, an open or 65 perforated cup-shaped stopper, slitted, scalloped, or notched around its margin, so as to be capable of pressing outward within a tube to hold it in place, substantially as set forth.

In testimony whereof I have hereunto subscribed my name.

HENRY D. CUSHMAN.
